Patented Apr. 18, 1922.

FIG. 1.

FIG. 3.

INVENTOR.
George S. King.

BY

Charles P. Griffin
ATTORNEY.

UNITED STATES PATENT OFFICE.

GEORGE S. KING, OF BERKELEY, CALIFORNIA.

AUXILIARY AIR SUPPLY FOR EXPLOSION ENGINES.

1,413,124.

Specification of Letters Patent. Patented Apr. 18, 1922.

Application filed November 11, 1920. Serial No. 423,424.

To all whom it may concern:

Be it known that I, GEORGE S. KING, a citizen of the United States, residing at Berkeley, in the county of Alameda, State 5 of California, have invented a new and useful Auxiliary Air Supply for Explosion Engines, of which the following is a specification in such full and clear terms as will enable those skilled in the art to construct 10 and use the same.

This invention relates to an auxiliary air supply for explosion engines and its object is to automatically vary the supply of air admitted to the engine to correspond with 15 the engine operating conditions at different speeds.

A further object of the invention is to provide means whereby the automatic part 20 of the apparatus may be thrown out of operation to permit an indefinite supply of air to pass to the engine when no fuel supply is necessary as occurs during the time that the automobile is running down hill.

It will be understood by those skilled in 25 the art that carburetors must be made to supply explosion engines with gas over considerable ranges of speed and power conditions. However, in order to have the engine start easily it must be supplied with a highly 30 explosive mixture of gas for low speeds and it is not possible with the ordinary carburetor to produce a carburetor completely automatic throughout all of the driving conditions so that some additional apparatus 35 is necessary to supply the added air necessary at high speeds, if the least fuel is to be used.

In the present instance, this apparatus 40 provides automatic control of the added air necessary to produce an economical operation of the motive power and also provides means whereby the driver may by hand increase the air supply indefinitely, thereby causing the engine to operate as a brake 45 when the car is running down hill and avoiding the use of any fuel at all at such times as that.

Other objects of the invention will appear as the description proceeds. 50 An embodiment of the invention is shown in the accompanying drawings in which the same reference numeral is applied to the same portion throughout, but I am aware that there may be modifications thereof.

55 Figure 1 is a side elevation of an engine

having this auxiliary air supply applied to its intake manifold.

Fig. 2 is a plan view of the auxiliary air supply.

Fig. 3 is a side elevation of the air supply. 60

Fig. 4 is a vertical sectional view of the auxiliary air supply.

Fig. 5 is a diagram indicating the conditions of running of the automobile engine from zero speed to a speed of 2000 R. P. M. 65 corresponding with a car speed from zero to 55 miles per hour.

Examining the diagram first, the vacuum attained is indicated at the vertical coordinate and the throttle opening corresponding 70 with the given miles per hour is indicated increasingly to the right on the horizontal coordinate. The vertical coordinate A increases from one to ten or twelve pounds per square inch in ordinary cars, some cars

75 having a greater vacuum than others at the idling speed. Also in ordinary cars the horizontal coordinate B will cover a speed of from one to fifty miles per hour, seldom exceeding that. It will be seen of course, 80 that with the throttle closed and the engine stopped, there is no movement of explosive gas into the engine cylinders, however, as soon as the engine is started and begins to run at its idling speed, the vacuum rapidly 85 goes up to the maximum, depending upon the kind of engine used, and the kind of carburetor used, the maximum point being indicated at C, from which point as the car's speed increases up to 28 miles per hour that 90 the car tested, the vacuum rapidly drops off, and at speeds above that, there is substantially no increase in the vacuum produced, the throttle then being wide open.

95 This curve means, that at the highest vacuum point no additional air must be supplied, since at that moment the mixture supply is very rich and any excess air would simply tend to make the engine run faster than is needed.

100 Also at the point D where the throttle is wide open the minimum pressure is found, the auxiliary air supply must be arranged to supply some further air than the carburetor itself will supply because with the engine running rapidly, the mixture may be made as lean as will maintain the given speed. The apparatus therefor must regulate itself under such conditions, but when no power at all is required, manual means must be 105 110

provided to prevent its normal operation with the throttle closed and supply the engine with such free air as is necessary to prevent any fuel gas from going into the engine.

The numeral 1 indicates an explosion engine having the exhaust manifold 2, inlet manifold 3 and carbureter 4. This auxiliary air supply apparatus is indicated generally 10 at 5 and is applied to the inlet manifold of the engine by means of a pipe 6 which is connected therewith. The auxiliary air supply apparatus consists of a casing having a chamber 7 therein, which chamber has a 15 connection at 8 and 9 with a passageway 10. The bottom of the chamber is closed by means of a plug 11, which has an opening thereon provided with an annular seat upon which a plunger valve 12 rests when the engine is not running.

The plunger valve has an opening from end to end indicated at 13 to prevent it from being too easily lifted by the suction of the engine and it also fits the chamber loosely 25 enough to permit a certain amount of air to pass.

The operation of the plunger valve is regulated by means of a screw 13' which obstructs the passage 8 much or little as may 30 be necessary and as will be seen later.

A pipe 14 connects the top of the casing 5 with a T 15. Said T being connected on its side with a pipe 6 which extends to the inlet manifold. The top of the T has a 35 valve casing 17 secured thereto, said valve casing having an arm 18 to which is pivotally connected a bell crank lever 19 bearing upon the top of the valve stem 20. The valve stem 20 is held normally raised by the 40 spring 21 which holds the valve 22 seated to prevent air from passing into the auxiliary air supply. The lower end of the rod 20 is arranged to be of such length as to unseat the plunger 12 whenever additional air 45 is needed, to prevent the engine from getting any fuel thus providing two means for supplying the engine with free air whenever the car is running down hill.

In operation as the engine is under a considerable vacuum at starting, the plunger valve 12 will rise and prevent any air from passing to the engine through this auxiliary air supply. As the vacuum decreases the plunger valve will fall and more or less air 55 will be permitted to pass through the hole 13 and passageway 8 to the engine as the speed requirements determine are necessary, and this will be regulated by screw 13'.

If the speed becomes great enough the 60 plunger 12 will fall so that this auxiliary air supply apparatus will permit the entire area of the passageway 8 to supply the engine with auxiliary air as regulated by the screw

13' and whenever the car is running down hill the driver may pull on the cord 23 and thereby still further reduce the vacuum and prevent the car from getting any fuel from the carbureter.

What I claim is as follows, but various modifications may be made in the construction shown in the drawings and above particularly described form, within the purview of my invention:

1. An auxiliary air supply for explosion engines comprising a casing, pipes connecting said casing with the inlet manifold of an explosion engine, a weighted valve in said casing, a screw for regulating the quantity of air allowed to pass through said casing to the explosion engine and manual 80 means for unseating the valve to permit an indefinite supply of air to pass to said engine.

2. An auxiliary air supply for explosion engines comprising a casing, pipes connecting said casing with an inlet manifold of an explosion engine, and a weighted valve in the casing to determine the quantity of air admitted to the explosion cylinder during the running of the engine, the casing having a by-pass with openings thereinto above and below said valve, the valve being arranged to permit a small quantity of air to pass it in the casing.

3. An auxiliary air supply device for explosion engines comprising a casing with a hole in its bottom having a by-pass from its upper to its lower portion, pipes connecting said casing with the inlet manifold of an explosion engine above the carbureter and a 100 weighted valve in the casing movable to a position from the bottom of the casing to the top of the casing to prevent the access of air to the explosion engine cylinder whenever the vacuum within the inlet manifold 105 rises above or falls below a predetermined amount, the valve being arranged to close the hole in the bottom of the casing when the engine is running at lower vacuum.

4. An auxiliary air supply for explosion 110 engines comprising a casing with a hole in its bottom having a by-pass extending from one end to the other end thereof, a valve movable in said casing to determine the quantity of air supplied to the engine under 115 different running conditions and a screw movable into the by-pass to regulate the quantity of air passing therethrough, the valve also permitting a small amount of air through the casing to pass it when it is un-seated.

In testimony whereof I have hereunto set my hand this 24th day of October A. D. 1920.

GEORGE S. KING.
